US0D1038145S

(12) **United States Design Patent** (10) Patent No.: **US D1,038,145 S**
Liao (45) Date of Patent: ** Aug. 6, 2024

(54) **DISPLAY SCREEN OR PORTION THEREOF WITH GRAPHICAL USER INTERFACE**

(71) Applicant: **Acer Incorporated**, New Taipei (TW)

(72) Inventor: **Ting-Chun Liao**, New Taipei (TW)

(73) Assignee: **Acer Incorporated**, New Taipei (TW)

(**) Term: **15 Years**

(21) Appl. No.: **29/852,382**

(22) Filed: **Sep. 7, 2022**

(30) **Foreign Application Priority Data**

Aug. 11, 2022 (TW) 111303954

(51) LOC (14) Cl. **14-04**

(52) U.S. Cl.

CLAIM

The ornamental design for a display screen or portion thereof with graphical user interface, as shown and described.

DESCRIPTION

The FIGURE is a front view of a display screen or portion thereof with graphical user interface showing my new design.

The dot-dash broken line illustrates a display screen or portion thereof and forms no part of the claimed design. The dashed broken lines illustrate portions of the graphical user interface that form no part of the claimed design.
